UNITED STATES PATENT OFFICE.

ALEXSON STEPHEN, OF CHICAGO, ILLINOIS.

NEEDLE THREADER.

Application filed October 26, 1925. Serial No. 64,865.

My invention relates to improvements in needle threading devices, and it consists in the combinations, constructions, and arrangements herein described and claimed.

5 An object of my invention is to provide a simple device by means of which an ordinary sewing needle may be threaded with very little effort, and even by one whose eyesight is very poor.

10 A further object of my invention is to provide a device of the type described in which the operation of the parts is made certain by the fact that the needle is guided into exact position for receiving the hook which pulls the thread through the eye.

15 A further object of my invention is to provide a device which may be conveniently held in one hand, thereby permitting the other hand to manipulate the hook member.

20 Other objects and advantages will appear in the following specification, and the novel features of the invention will be particularly pointed out in the appended claim.

25 My invention is illustrated in the accompanying drawings, forming part of this application, in which—

Figure 1 is a section through a portion of the needle threading device, the holding member being shown in elevation,

30 Figure 2 is a top plan view of the device, and

Figure 3 is an enlarged section along the line 3—3 of Figure 1.

In carrying out my invention, I provide 5 a body portion 1 of the general shape shown in the drawings. This may be made of metal, celluloid, wood, or any suitable material. As will be observed, it is substantially cylindrical in shape, tapering however

10 toward the bottom. At the bottom, the device is rounded off and terminates in a substantially flat holding member 2 which is preferably provided with an opening 3. The opening 3 serves a double purpose; it 15 permits the thumb and finger to get a good grip on the holding device, and it serves as a means for hanging the needle threader on a nail or other suitable support when not in use, or for attachment to a chain or string.

The body portion has a bore 4 extending downwardly from one end. It will be observed that this bore tapers from the end toward the bottom. Near the bottom, however, the bore flattens out; that is to say, 15 it is of an oblong shape, as shown in Figure

3. Extending inwardly from each side are tapered passages 5 and 6. The passages 5 and 6 have a common central axis.

Near the top of the body portion 1 is a 60 cutaway portion 7 to provide a shoulder on which is supported a spiral spring 8, preferably by means of a loop of wire 9. One end of this spring is secured to the body 1, the opposite end being bent in U-shape, as 65 shown at 10, and is provided with a small hook 11. It will be observed that the portion of the wire near the hook is made thinner.

From the foregoing description of the 70 various parts of the device, the operation thereof may readily be understood. A needle, such as that shown at 12, is placed in the bore 4 with the eye portion extending downwardly. The handle or holding member 2 is grasped and the device is shaken so that the needle will pass downwardly into the lower flat portion of the bore. The needle, owing to the curvature of the bore, automatically adjusts itself so that the eye of 75 the needle, when the latter has reached the bottom of the bore, is in alignment with the passages 5 and 6. The U-shaped spring member 10 is now brought downward and its end is thrust through the passage 5, through the eye of the needle, and through the passage 6, the thread 13 is caught on the hook, and the U-shaped spring member is drawn backwardly, drawing the thread through the eye 80 of the needle. The thread is then detached from the hook and the needle drawn out, drawing with it as much of the thread as desired from the spool 14, when the thread 85 may be broken off and entirely detached from the needle threading device.

That the device is very efficient has been proved in practice by a model. Many times it is only necessary after passing the hook through the passages 5 and 6 to retract it and then pull the needle out immediately, thus pulling the thread from the hook and from the spool. I have found that this device in actual practice will work with needles of various sizes, since the device is so constructed that with small needles, as well 90 as large ones, the passages 5 and 6 are in alignment with the eyes which will permit the thread to be drawn through very readily.

I am aware that devices for threading sewing machine needles which are held in a 100 stationary position have been made before. The present device, however, is adapted for

threading all kinds of needles, and especially those which are not held in a stationary position. In the drawing, I have shown the flat part of the needle as beginning just above the passages 5 and 6. Obviously this flat portion may be extended further up without departing from the spirit of the invention, the main purpose being to so form the bore 4 as to cause the needle to be guided automatically into position with the plane of the flat portion of the needle at right angles to the passages 5 and 6 so as to bring the eye into alignment with these passages.

I claim:

10. A needle threading device comprising an elongated body portion having a bore extending from one end toward the other, said bore being of a length sufficient to receive

the major portion of a needle, said bore tapering from the outer end toward the opposite end and terminating in an oblong reduced portion, said body portion being provided with transverse aligned passages tapered from the outer edge of the body portion, said transverse aligned passages communicating with said oblong portion of the bore, a U-shaped spring-actuated member having a hook at one end arranged to pass through said passages and through the eye of the needle, and a flat plate-like holding member integral with said body portion at the end thereof near the transverse passages, the plane of said holding member being parallel with the axis of the transverse passages.

ALEXSON STEPHEN.
